UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y. A CORPORATION OF DELAWARE.

ACCUMULATOR RECIPROCATOR FOR TABULATING MACHINES.

Original application filed March 28, 1917, Serial No. 153,142. Divided and this application filed April 3, 1918. Serial No. 226,498.

To all whom it may concern:

Be it known that I, WILLIAM W. LASKER, a citizen of the United States, residing in Brooklyn, in the county of Kings and State of New York, have invented certain new and useful Improvements in Accumulator Reciprocators for Tabulating Machines, of which the following is a specification.

This invention relates to a printing tabulator of the kind adapted to be controlled by perforated cards, and relates more particularly to matter divided from my pending application Serial No. 158,142, filed March 28, 1917, for printing tabulators.

The invention herein described relates particularly to the mechanism for reciprocating the accumulator carriage, of said printing tabulator and, therefore, only as much of the printing tabulator is mentioned herein as is necessary to show the relation between the matter of the original application and the matter divided out and claimed herein.

While herein and in said application minute details of one of many possible embodiments of the inventions are described, the invention is not limited to these since various changes may be made in the details of construction and combination without departing from the spirit and scope of the invention as claimed.

One object of the present invention is to improve generally apparatus of this kind.

A further object of the present improvement is to devise a printing tabulator having a reciprocating accumulating carriage and means for reciprocating this carriage by two different actions, one action controlling the carriage for accumulating and the other action controlling the carriage for taking a total.

A further object of the present improvement is to construct a printing tabulator embodying a novel form of shift mechanism whereby the accumulating and printing elements of the machine are shifted from accumulating position to total taking position and vice versa.

Still further objects and advantages of the present improvement will be set forth in the following description and drawings in which,

Fig. 1 is a side elevation of the printing

and calculating machine constituting a part of the printing tabulator.

Fig. 2 is an interior side elevation partly in section of the type setting and calculating elements and showing the parts thereof after the completion of the printing operation.

Fig. 3 is an enlarged perspective view of the total taking shaft and the activating arms for the accumulating mechanism.

Fig. 4 is a fragmental vertical sectional view taken in a vertical plane passing through the total taking shaft.

Fig. 5 is a vertical sectional view showing the total taking shaft shifted into position to take a total.

Fig. 6 is a detail view of one of the control-operating cams.

The invention herein relates to a printing tabulator which is adapted to be actuated by perforated cards, which in their passage through the machine operate elements for setting up type commensurate with the designations on the card, and actuate an accumulating mechanism for accumulating therein the data recorded on the card perforations whereby the total accumulated data may be computed and then printed by the printing elements of the machine.

The embodiment illustrated in said co-pending application comprises a main frame, the card feeding mechanism, the card analyzing mechanism, and an upper base 10 (Fig. 1) on which the accumulating and printing mechanism 12 hereinafter to be described and the paper printing carriage 13 are mounted.

The cards to be analyzed are disposed in a receptacle and are fed to the analyzing mechanism in which, as shown in said co-pending application, analyzing pins which find perforations in the cards being analyzed, pass upwardly therethrough and engage extension pins, which in turn actuate registering stops 14. After the cards have been analyzed they are discharged into a suitable receptacle.

The first step in the operation of the type setting and tabulating mechanism, consists in the pushing up of the various stop pins 14 (Fig. 2) by means of the extension pins, which are actuated by the various perforations in the cards as they pass through the machine. A specific description of the stop

UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

ACCUMULATOR RECIPROCATOR FOR TABULATING MACHINES.

Original application filed March 28, 1917, Serial No. 153,142. Divided and this application filed April 3, 1918. Serial No. 226,498.

To all whom it may concern:

Be it known that I, WILLIAM W. LASKER, a citizen of the United States, residing in Brooklyn, in the county of Kings and State of New York, have invented certain new and useful Improvements in Accumulator Reciprocators for Tabulating Machines, of which the following is a specification.

This invention relates to a printing tabulator of the kind adapted to be controlled by perforated cards, and relates more particularly to matter divided from my co-pending application Serial No. 158,142, filed March 28, 1917, for printing tabulators.

The invention herein described relates particularly to the mechanism for reciprocating the accumulator carriage, of said printing tabulator and, therefore, only as much of the printing tabulator is mentioned herein as is necessary to show the relation between the matter of the original application and the matter divided-out and claimed herein.

While herein and in said application minute details of one of many possible embodiments of the inventions are described, the invention is not limited to these since various changes may be made in the details of construction and combination without departing from the spirit and scope of the invention as claimed.

One object of the present invention is to improve generally apparatus of this kind.

A further object of the present improvement is to devise a printing tabulator having a reciprocating accumulating carriage and means for reciprocating this carriage by two different actions, one action controlling the carriage for accumulating and the other action controlling the carriage for taking a total.

A further object of the present improvement is to construct a printing tabulator, embodying a novel form of shift mechanism whereby the accumulating and printing elements of the machine are shifted from accumulating position to total taking position and vice versa.

Still further objects and advantages of the present improvement will be set forth in the following description and drawings in which,

Fig. 1 is a side elevation of the printing

and calculating machine constituting a part of the printing tabulator.

Fig. 2 is an interior side elevation partly in section of the type setting and calculating elements and showing the parts thereof after the completion of the printing operation.

Fig. 3 is an enlarged perspective view of the total taking shaft and the activating arms for the accumulating mechanism.

Fig. 4 is a fragmental vertical sectional view taken in a vertical plane passing through the total taking shaft.

Fig. 5 is a vertical sectional view showing the total taking shaft shifted into position to take a total.

Fig. 6 is a detail view of one of the control-operating cams.

The invention herein relates to a printing tabulator which is adapted to be actuated by perforated cards, which in their passage through the machine operate elements for setting up type commensurate with the designations on the card, and actuate an accumulating mechanism for accumulating therein the data recorded on the card perforations whereby the total accumulated data may be computed and then printed by the printing elements of the machine.

The embodiment illustrated in said co-pending application comprises a main frame, the card feeding mechanism, the card analyzing mechanism, and an upper base 10 (Fig. 1) on which the accumulating and printing mechanism 12 hereinafter to be described and the paper printing carriage 13 are mounted.

The cards to be analyzed are disposed in a receptacle and are fed to the analyzing mechanism in which, as shown in said co-pending application, analyzing pins which find perforations in the cards being analyzed, pass upwardly therethrough and engage extension pins, which in turn actuate registering stops 14. After the cards have been analyzed they are discharged into a suitable receptacle.

The first step in the operation of the type setting and tabulating mechanism, consists in the pushing up of the various stop pins 14 (Fig. 2) by means of the extension pins, which are actuated by the various perforations in the cards as they pass through the machine. A specific description of the stop

pins, their supporting means, and the means for returning them to normal position after they have set in motion various other parts of the type setting and tabulating mechanism is given in said co-pending application.

The registering stops 14 correspond in number to the extension pins except that there are no extension pins or registering stops 14 to correspond with the analyzing pins that analyze the zero perforations in the cards. Each row of registering stops 14 has a zero stop 16 associated therewith, which is normally in zero stopping position and will remain so unless one of the registering stops 1 to 9 inclusive associated therewith is actuated and therefore it is unnecessary for a zero analyzing pin to actuate or cooperate with a zero stop 16.

Herein the part of the accounting machine to the left of Fig. 2 will be considered the forward part of the machine, while that to the right of Fig. 2 will be considered the rear of the accounting machine.

The registering stops 14 in the present instance are arranged in a suitable number of rows having ten stops in each row, the stops of each row corresponding to the integers 9 to 1 inclusive and zero, the stop 9 being at the forward end of the machine and the zero stop at the rear end thereof. The stops 14 corresponding to the integers 1 to 9 inclusive are each composed of a flat body portion comprising a head having forwardly projecting portion 17 a cam face 18, a small rectangular shaped abutment 19 made on one side of the pin and adjacent to its upper end, an elongated body portion 20, and a lower restoring notch 21 on the rear edge thereof. The stops 14 have their projections 17 normally resting on an upper stop plate 22 and extend down through a lower stop plate 23. The stop plates 22 and 23 have openings therein corresponding in number to the stops 14 and zero stop 16 in registry with each other whereby the pins may reciprocate through them.

The stop plates 22 and 23 are indirectly supported on the cheek plates 34.

The zero stops 16 are formed somewhat similar to the stops 14 and have a forward projection 36 at their upper end and a cam face 37 on the forward edge extending upward from the extension 36 and a recess 38 in its edge.

Means are provided for anchoring the various registering stops 14 that are actuated by the extension pins and also holding the zero stops 16 in position for causing an actuation of the corresponding type setting and tabulating elements. These anchoring means are fully shown and described in said co-pending application and are not claimed herein. The zero stops 16 are normally disposed in raised position and whenever a stop 14 is actuated to the

raised position by means of the plungers 12, simultaneously therewith the zero stop 16 in that row will be lowered. In order to accomplish this result, an elongated lever 62 (Fig. 2) is provided for each row of stops 14, which lever is provided with a plurality of lugs 63 arranged in a straight line and all extending in the same direction, each lug 63 also extending into one of the recesses 21 of the stop pins 14. The front ends of the levers 62 are pivoted on a suitable shaft which is supported within the cheek plates 34 of the machine. The rear ends of the lever 62 are each provided with a slot 67 which receives a lug 66 carried by a link 68. The links 68 are pivoted on a shaft 69 supported by the cheek plates 34. The front end of each of the links 68 is provided with a lug 70 which is arranged to slide within a recess 38 formed in the rear edge 85 of the naught stop 16 with which the link 68 is associated.

Supported by the cheek plates 34 is a comb plate 71 the upper end of which is slotted to permit the lever 62 to extend therethrough and be guided thereby. A coil spring 71' is strained between each lever 62 and the lower edge of the said plate 71 for the purpose of normally raising its naught stop 16 into the position shown in Fig. 2. When one of the stops 14 is raised, the actuation of the lever 62 by means of the cooperation of the slot 21, carried by the stop, with the lug 63, carried by the lever, will cause the link 68 to be actuated which will in turn lower the stop 16 of the row in which the stop pin 14 has been raised.

As has been heretofore described the first action that takes place when the machine is started, is the raising of the various stop pins 14 by the actuation of the extension pins which are in turn controlled by the perforations in the cards passed through the machine. After a card has transferred its data to the pins 14 by raising them, and has passed from the machine, means are provided for returning the raised pins 14 to their normal lower position for actuation by the next incoming card. The means for returning the stop pins to their normal position is described in detail in said co-pending application, and comprise the lever 72 having a bifurcated lower end 73 which latter straddles the main drive shaft 74 which provides the driving means, for the entire type setting and calculating mechanism. This lever 72 is provided with a pin 72' on which is rotatably mounted a roller 75 arranged to roll within a cam slot 76 in a suitable cam on the shaft 74. The lever 72 operates means described in said co-pending application, (not shown or claimed herein) whereby the stops 14 which have been set by the perforated cards, are released by the afore mentioned anchoring means after they have performed 120 125 130

their functions. As soon as the pins 14 are freed, the lever 62 will be pulled down by means of the coil spring 71, and in its downward movement the lugs 63 carried thereby will engage the slots 21 of the stop pins 14 and pull them downward to their normal lowered position.

The naught stop pins 16 are arranged to normally retain or hold back reciprocating rack bars 82, which during their reciprocation actuate type setting elements. As heretofore described, the raising of a stop 14 will lower the naught stop in that row so that upon the actuation of a stop 14, the reciprocating rack-bar associated therewith will be released and be permitted to be moved forward until it engages the raised stop 14.

During their forward reciprocation, the rack bars have actuated the type setting elements 20 and upon being stopped by the raised stop pins will hold the type setting elements in a position to set type corresponding with the number of the raised stop pins. A detailed description of the reciprocating rack bars 25 and their connection and cooperation with the naught stops, stop pins and type setting elements will now be described.

The reciprocating rack bars each comprise a relatively thin bar shaped body portion 82 under which extends a transverse bar 84 secured to the cheek pieces 34, and on which the bars 82 slide. A transverse bar 85 is also provided which serves as a support for the forward end of the bar 82. The bar 85 is rigidly fastened to the cheek plates 34. A second relatively thin bar shaped member 86 is pivoted at its front end to a pivot 87 carried by the front end of the bar 82.

The upper edge of the bar 86 is provided 40 with a recess 88 to receive a bar 89 which is reciprocated by means hereinafter to be described, and during its reciprocation will move both the bar 82 and the bar 86 connected thereto. The bar 86 is provided with 45 a cut away portion 90 so as to lessen the depth of the said bar to enable it to slide above the shaft 84 and at the same time permit the outer ends of the bars 82 and 86 to remain parallel with each other. A spring 50 91 is strained between the free end of the bar 82 and a vertically extending arm 92 which is made integral with the inner end of the bar 82.

A horizontally extending pin 96 is carried 55 by one side face of the bar 82 which is adjacent to the bar 86 and pivotally mounted upon which is a bell crank lever 97, the outer end of which is provided with a horizontally extending pin 98 which is reciprocatively 60 movable in a slot 99 made in the bar 86. The other end of the lever 97 is provided with a lug having a cam front face 101 and a right angular notch forming a rest 103 (Fig. 2).

The upper edge of the bar 82 is provided 65 with an upstanding abutment 104 having a

vertical front wall 105 and an inclined or cam rear wall 106. The bottom edge of the bar 82 is provided with an abutment 104' provided with a vertical front wall 105' and a cam rear wall 106' the purpose of which 70 will be hereinafter set forth.

The bar 89 which as heretofore described, is for the purpose of reciprocating the bars 82 and 86 and is itself reciprocated in the following manner, reference especially being made to Fig. 1.

The bar 89 which is rectangular in cross section is rigidly connected at each end to a slide 107, which is reciprocated between rollers 108 forming guideways therefor. A slot 109 is made in each cheek plate 34 which receives a roller 110 revolvably mounted on the shaft 111 secured to the rear end of the said slides 107. The front end of the slides 107 are provided with horizontally extending pins 112, which enter in slots 113 formed in the upper ends of levers 114, the lower portion of which are triangularly shaped, one corner being pivoted to stud shafts 115 carried by each cheek plate 34. 85 The other corner of the triangular shaped levers 114 carries a roller which is arranged to roll within a suitable cam groove in a cam carried on the shaft 74.

Returning now to the rack bars 82, the top edge of the forward portion of each of said bars 82 is provided with gear teeth 119 which are in mesh with a gear 120 (Fig. 2) secured to a type segment 121, each of which has a bearing on a transverse shaft 100 122 carried between the cheek plates 34. The segments 121 have an arc shaped rear edge provided with gear teeth 123 which will hereafter be described. The front edge of the segments 121 are also made arc shaped and are provided with rectangular notches to receive the upturned ends of type 126. The rear ends of the type are also provided with a laterally turned portion 127 which is arranged to fit within rectangular openings in said segments. A flat arch shaped plate 128 is arranged to fit against the type 126 and to hold their lateral portions in engagement with said notches and openings respectively. Reading from the upper edge of the type carrying portion of the segment, the type carried thereby read in sequence, the first type being zero, the next "1" the next "2" etc., the last type on the segment being numbered "9".

A description of the operation of the stop pins, the reciprocating rack bars and the oscillating type segments will now be given. Normally the bars 82 are held in their rearward position by the engagement of the vertical walls 105' of the abutments 104' with the notches 38 in the upper end of the naught stops. All of the type segments are then in a position to print ciphers. Although each spring 91 is exerting tension 130

to lift its bar 86 nevertheless this bar is held to the limit of its downward movement due to the fact that the rest 103 of the bell crank lever 97 will be on top of the naught stop 16 which holds the said bell crank 97 at the limit of its downward movement by means of the pin 98 carried by the member 82 and the slot 99 in the bar 86. As soon as any of the stop pins 14 are raised by means of said pin extensions, actuated by means of a card passing through the machine, the naught stop 16 in that row is lowered simultaneously, as has been heretofore explained. The downward movement of the naught stop 16 frees the abutment 104 permitting the bar 82 to be carried forward. Simultaneously with the disengagement of the abutment 104 and the stop pin 16, the lever 86 is raised by means 20 of the spring 91 which in its movement moves the notch 88 to fit against the front side of the reciprocating bar 89. When the parts are in their normal position, the bar 89 is at the limit of its rearward movement 25 and rests against the vertical wall 105 of the abutment 104 as disclosed in said co-pending application. As soon as the notch 88 engages the reciprocating bar 89, the said bar is locked between it and said vertical wall 105 so that when the said bar 89 is reciprocated by means of the lever 114 and its associated parts, heretofore described, the bars 82 and 86 will also be moved forward. Simultaneous with the forward movement 30 of the bar 86 the bell crank 97 is moved downward. As the bar 89 is reciprocated by the lever 114, the said bars 82 and 86 will be carried with it until the cam face 101 of the bell crank engages the rectangular abutment 19 of the stop pin 14 which has been raised. This contact lifts the bell crank 97 and lowers the rod 86 against the tension of the spring 91 which in its downward movement releases the reciprocating bar 89. As soon as the bell crank 97 has been raised, the vertical wall 105 of the abutment 104 will engage the rear end of the raised stop pin 14 and prevent the bar 82 from moving further. Since the reciprocating bar 89 is released as the bar 82 is stopped, the bar 89 will continue its forward movement although the bar 82 and the lever 86 have been stopped. This is for the purpose of freeing the bars 82 and 86 from the reciprocating member 89 as they engage the stop pins in their forward position and thereby permitting the bar 89 to carry all other bars 86 forward which have not been freed from the bar 89 in the manner here- 45 tofore described.

Due to the rack teeth 119, as the bar 82 is moved forward, the type segment 122 is oscillated through the medium of the gear wheel 120 as heretofore described. After all 50 of the type segments have been set by the

stop pins in position to print data transferred thereto from the cards, means is provided for locking and alining the type segments so that they may not move during the printing operation. This locking and alining means will now be briefly described.

The extreme upper end of the lever 72 is provided with a knife shaped transversely extending arm 130 slidably mounted within a slot 131, within the cheek plates 34. Both the slot 131 and the knife shaped member 130 which is herein termed a detent, are arranged radial to the gear teeth 123 of the type segments and lock the said segment from moving, and line up the type carried thereby. The locking of the printing segments and the releasing of the stops 14, is brought about simultaneously so that the reciprocating members may be free to be moved back to their original positions after printing without engaging any stop pins whatever except the naught stops 16. A mechanism is provided for preventing all of the ciphers to the left of the digit last set up by the stop pin from being printed. Or in other words, a mechanism is provided for retracting all of the segments out of printing position which have been left against the naught stops as the released bars 82 start on their forward movement. Since this mechanism is described in said co-pending application and does not directly relate to the non-print of items that are accumulated, a description thereof is not given here. The parts 132, 139 and 183 relate to this mechanism. Means are provided for lowering the bars 86 so as to raise the bell cranks 97 so that when the bars reach the limit of the rearward stroke the rest 103 will be in position on top of its naught stop which is in its raised position as shown in Fig. 2.

The means for lowering the bars 86 and lifting the bell cranks comprises a transverse bar 163 (Fig. 2) which is arranged above the upper edge of the bars 86 being rigidly carried by the upper ends of slide levers 164 arranged adjacent the inner face of each cheek plate 34 which, during their downward movement, slide the bar 163 in slots 165 made in the said cheek plates. The slots 165 are of a length sufficient to permit the bar 163 to move down in contact with the upper edge of the bars 86 and force them downward. The lower ends of the levers 164 are provided with pins 166 which project through slots 167 in the cheek plates 34 and 35. The levers 164 are reciprocated up and down by means of levers 168 arranged adjacent the inner face of the cheek plates 34 and have bifurcated rear ends 169 which straddle the pins 166. The levers 168 are pivoted at 170 to each cheek plate 34 and are oscillated by suitable connecting mechanism driven from a cam on the shaft 74.

The accumulating elements of the machine

are arranged to be operated during the rearward movement of the bars 82. A description of this mechanism is given in detail in said co-pending application, and may, therefore, be briefly mentioned here.

The accumulating mechanism comprises a reciprocating carriage having spaced vertically arranged cheek plates 189 which are arranged within and adjacent to the cheek plates 34 respectively as is shown in Fig. 2. At the lower part of the forward end of the cheek plates 189 is mounted a transverse horizontally extending shaft 192, the outer ends of the shaft 192 projecting through longitudinal slots 193 (Fig. 1) in the cheek plates 34. Upon the shaft 192 are mounted a transverse spacing collars which are rigidly held together between the cheek plates 191 by means of collars 194 which clamps against the outer side of the cheek plate 191 by means of a nut 195. Revolubly mounted in each of the spacing collars are gear wheels 197 each having ten gear teeth 198 thereon. One side face of each of the gear wheels 197 is provided with an annular collar 199 having on its periphery an abutment 200 providing a radial face 201 and an inclined cam face 202. The abutment 200 is made on the periphery of the collar 199 so that it lies adjacent gear tooth "0" of the gear teeth 198. The collars 199 are also provided with an abutment 203 having a rounded face, and this abutment is arranged adjacent gear tooth "5" and diametrically opposite the abutment 200. The functions of the abutments 200 and 203 will be hereinafter set forth.

The rear end of the cheek plates 189 are provided with longitudinal slots 205 which receive a guide rod 206 rigidly carried by the cheek plates 34 and 35.

Means are provided for reciprocating the accumulating carriage backward and forward on the guide rod 206 and the shaft 192 which carries the accumulating gear wheels. This means comprises levers 207 (Figs. 1 and 3) which have their upper ends 209 respectively supporting the shaft 192. The lower ends of the levers 207 are pivoted to stud shafts 211 carried by levers 215 which have horizontally extending portions 217 (Figs. 4 and 5) which extend inwardly toward each other and are provided with vertically extending relatively rectangular shaped plates 219 pinned together at their upper and lower ends by means of pins 221. The said plates 219 are provided with registered openings 223 and 224 to receive a cam shaft 225 loosely mounted on a shaft 226 which passes through its center. Rigidly mounted upon the shaft 226 are collars 227 and 228 (Fig. 3) which abut against the ends of the cam shaft 225 and are held in locked position by means of set screws 229. The collar 227 is pro-

vided with an annular groove 230 to receive the bifurcated end 231 (Fig. 2) of a lever 232 which is pivotally mounted at 233 to the frame work 234.

The lever 232 intermediate its ends is provided with a rectangular cage 235 within the walls of which is reciprocatably mounted a plunger 236 having a cam engaging head on its upper end. A spring 237 is compressed between the inner face of the said cam engaging head and the wall of the rectangular cage. The spring is normally held compressed by means of a bell crank 238 pivoted to the lever 232, one end 239 of which is adapted to engage a collar 241 carried on the inner end of the reciprocating plunger 236. The other arm of the bell crank 238 is provided with a key 140 which upon being pressed, disengages the end 239 from the collar 241 and permits the plunger 236 to be forced upwardly under action of the spring, whereupon the plunger enters a spiral cam groove 244 (Fig. 6) in the periphery of the cam 77. As the cam head runs in the groove 244 the lever 232 will be pushed to one side by the said groove and thereby cause a sidewise movement of the lever 232 which will slide the cam shaft 225, for a purpose to be hereinafter set forth. As the cam reaches the end of its revolution, an abutment 245 secured therein and having an inclined face 246 will engage the end of the plunger head and force it down whereupon the collar 241 snaps it back of the said lever 238 and is held in its locked position (Fig. 2). A coil spring 248, strained between the end of the lever 241 and the upper edge of the lever 232, normally holds said end in an upward position to be engaged by the collar 241. The levers 207 and 208, as before described, are for reciprocating the accumulating carriage. These levers are pivotally mounted upon a transverse shaft 250 which is mounted in the cheek plates 34. Between the said levers 207 and pivotally mounted on the shaft 250 are the inner contacting ends 251 of levers 253 and 254 respectively which have openings 255 and 256 to receive the cam shaft 225. Near their inner ends, the levers 253 and 254 are provided with offsets 257 whereby the parts that receive the cam shaft 225 are spaced apart. The outer ends of the levers 253 and 254 have upwardly turned portions provided with revolubly mounted rollers 258 and 259 respectively. The roller 259 is adapted to run in a cam groove 260 in the cam 118 which, during the revolution of the said cam, transmits a rocking motion to the lever 254 which through the medium of the levers 215 and 207 reciprocates the accumulating carriage. When the said accumulating carriage is being reciprocated by the lever 254, the accumulating elements thereof are actuated for accumulating pur-

poses only, as will be hereinafter more fully set forth, and consequently the lever 254 may be termed the "accumulating lever."

A coil spring 263 is strained between ears 5 264 carried by the lever 207 and the lever 215 for the purpose of normally holding a lug 266 carried by the lower edge of the lever 207 against the lower edge of an opening 267 made in the upper end of the lever 10 215. The springs 263 are of such strength that the levers 207 and 215 are for all practical purposes as though they were made as a single lever.

The roller 258 is revolvably mounted in a 15 cam groove 268 of a cam 269 which, during the revolution thereof, will transmit a rocking motion to the lever 253, which motion, through the medium of levers 207, will reciprocate the accumulating carriage. Since 20 the reciprocating carriage is reciprocated by the levers 253 only when taking the total this lever 253 may be termed the "total taking lever." The cam shaft 225 is provided 25 with an annular groove 271 having inclined side walls 272 and 273 respectively. The openings 223 and 224 form bearings for the cam shaft 225. The groove 271 is of a width greater than the space between the levers 253 and 254 so that only one of the said 30 levers at a time can have the walls of its opening 255 or 256 in contact with the periphery of the cam shaft 225. As for instance, when the cam shaft is shifted by the lever 232 and its associated parts, as heretofore described, and the lever 253 has the walls of its opening in engagement with the periphery of the cam shaft 225, the opening 256 in the lever 254 will not engage the periphery of the cam shaft 225 but will be free 35 within the groove 271 (Fig. 5). When the cam shaft 225 is shifted in the reverse direction, the levers 253 and 254 occupy the position shown in Fig. 4 in which case the lever 253 is shown loosely mounted in the groove 40 271 while the edges of the opening of the lever 254 are in engagement with the periphery of the cam shaft. Since both of the levers 253 and 254 are always being oscillated through the action of their cams 261, 45 the lever which is loosely mounted in the groove 271 may frequently not be in a position where its opening will exactly register to receive the cam shaft 225 when it is moved sidewise. Due to the inclined walls 50 272 and 273 of the annular groove 271, however, when the cam shaft 225 is moved sidewise in the opening in one of the levers 253 or 254, the edges of the said opening will 55 slide upon the inclined walls of the annular groove 271 until they come in position to receive the cam shaft. When the cam shaft is moved sidewise so as to place the edges 60 of the opening of the levers 253 or 254 in engagement with the periphery of the cam shaft, a positive connection will be made be-

tween the said lever and its cooperating levers 215, and the accumulating carriage reciprocated. At this time the other lever whose opening is loose in the groove 271 has no operative effect on its associated lever 70 207 for reciprocating the accumulating carriage. From the above it is apparent that the levers 253 and 254 are selectively locked, so to speak, to the cam shaft 225 for reciprocating the accumulating carriage, the lock 75 and release being actuated by the shifting of the cam shaft 225.

The purpose of the different cycles of the reciprocation of the accumulating carriage by two different levers, and its effect upon 80 the accumulating and printing mechanisms will be hereinafter explained.

Now will be considered the position of the parts in which the lever 254 is locked on the cam shaft 225 and the accumulating carriage is being reciprocated thereby for the purpose of accumulating. At this time the elements of the accumulating mechanism occupy the position shown in Fig. 2.

As is shown in this figure, the printing operation has been completed, and the other elements of the printing mechanism have been so set to permit a free passage of the reciprocating members 82 in a rearward direction. Before the members 82 move rearwardly however, the lever 254 is operated which will reciprocate the accumulating carriage forwardly until the accumulator wheels 197 have been brought into contact with the gear teeth 123 of the type segments. 100 The rearward movement of the bars 82 will then rotate the accumulating gear wheels 197 and turn the teeth thereon to an extent which corresponds with the type last set up by the type segments for printing. When 105 the rack bars 82 have reached the limit of their rearward movement, the lever 254 is again rocked to reciprocate the accumulating gear wheels, and bring the said accumulating gear wheels into engagement with a 110 transverse bar 272 which is carried by the cheek plates 34 and holds the said accumulating gear wheels against accidental shifting.

This reciprocation of the accumulating carriage backward and forward and the engagement and disengagement of the accumulating gear wheels with the gear teeth of the type segments takes place as the bars 82 are at rest.

However, when any of the accumulating gear wheels have made a complete revolution the inclined wall 202 (Fig. 2) of the abutment 200 carried by the said gear wheel has been brought into engagement with the inclined wall 273 made on the lower end 123 of an L-shaped lever 275, the said lever is rocked upwardly on its pivot 276 against the action of a coil spring 277 strained between the lever 275 and a transverse rod 278 carried between the cheek plates 189, nor- 130

normally holds the lever 275 in a horizontal position. In its horizontal position, the lever 275 holds a vertically extending lever 278 to the limit of its upward movement, the upper edge of the lever 275 engaging a lip 279 carried by the side of the lever 278, which movement is limited by the rod 277 carried by the cheek plates 189 and received in a longitudinal slot 280 in the upper end 10 of the lever 278. Said lip holds the said lever 278 in its said upward position against the tension of a coil spring 280' strained between the said lever and a transverse rod 281 carried between the cheek plates 189. A horizontally disposed comb plate 281' carried between the cheek plates 189 forms guide ways for the vertical extending levers 278. Pivoted to the lower end of the lever 278 is a lever 283, guided in a guide comb plate 284. The other end of the lever 283 is pivotally connected to the lower end of a lever 285 which is provided with an enlarged slot 286 receiving the transverse shaft 276. The upper end of the lever 285 is shaped to form a lever 287 which extends rearwardly in a relatively horizontal direction, and is pivotally mounted upon a transverse rod 289, carried between the cheek plates 34. A coil spring 290 strained between the lever 285 and a transverse rod 291 carried by the cheek plates 189, normally holds the outer end of the lever 287 in a downward position. The said outer end of the lever 287 is slidably mounted in a comb plate 292 and carries on its outer end a revolvably mounted roller 294 adapted to engage a stepped cam plate 295 provided with cam surfaces 295' which plate is reciprocated back and forth for lifting the roller 294 and rocking the lever 287 against the tension of the spring 290. The cam plate 295 is disposed between the cheek plates 34 and carries at its side edges rollers 296 which are adapted to roll in longitudinal slots 297 (Fig. 1) in the cheek plates 34. The means for reciprocating the cam plate 295 backward and forward comprises levers 298, pivoted to the cam plate at the point 299, and carry on their lower edges rack teeth 300 which mesh with a pinion 301, revolvably mounted upon a shaft 302 slidably mounted in a longitudinal slot 303 in the cheek plates 34. Rollers 304 prevent the upward movement of said levers 298 and keep the rack teeth in engagement with the pinion 301. The pinion 301 is also in mesh with stationary rack bars 305 fastened to the outer face of the cheek plates 34.

The shaft 302 is moved backward and forward in a slot 303 by means of a lever 307 which has a bifurcated upper end 308 receiving said shaft 302. The levers 307 are fulcrumed on stud shafts 309 carried by the cheek plates 34. The lower ends of the levers 307 are bifurcated as at 310 to straddle a transverse shaft 311 reciprocated in parallel slots 312 (Fig. 1) in the frame work 234. The transverse shaft 311 passes through the entire machine and is arranged to receive the levers 307 of each independent unit or zone. Lever 313 arranged on each side of the machine have one end 314 pivotally mounted on the transverse shaft 311 and their other ends provided with a longitudinal slot 315 to receive the main drive shaft 74. This end of each lever 313 is provided with a revolvably mounted roller 318 which is arranged to rotate in a cam groove 319 in the cam 77. As the main shaft 74 is revolved, the stepped cam plate 295 is, through the lever connections heretofore described, reciprocated back and forth. Due to the arrangement of the pinion 302 and the rack bars 298 and 305, the movement of the rack bar 298 is in ratio of two to one to the movement of the pinion 302 on the rack bar 305.

Returning now to the L-shaped lever 275, it will be seen that means is provided for locking the rear end of this lever in a downward position when the vertical portion 275 thereof has been raised by engagement with the abutment 200 carried by the accumulating gear wheels. This means comprises a bell crank lever 320 (Fig. 2) pivoted upon a transverse shaft 321 carried by the cheek plates 189. Horizontally disposed comb plates 322 guide these levers during their movement. A coil spring 324 strained between the upper end of the lever 320 and a transverse shaft 325 carried by the cheek plates 189 will normally pull the upper end of the lever 320 forwardly and hold it against the inner end of the lever 275. When the lower end of the lever 275 is raised as heretofore described, the vertically extending portion 336 thereof will snap within a notch 327 formed in the front edge of the lever 320 and hold the said portion 336 in its downward position. The other arm 328 of the bell crank 320 is adapted to come in contact with the transverse shaft 206 and upon doing so will move the upper end of the lever rearwardly against the tension of the spring 325 releasing the vertically extending portion 336 of the lever 275 from the notch 327 and permit the said lever 275 to occupy its horizontal position under the action of the spring 277.

A description of the operation of the carry over mechanism which has just been above described will now be given. After the accumulating gear wheels have made a complete revolution and the abutment 200 thereon comes in contact with the cam face 273 of the vertically extending portion 274 of the lever 275 the said lever will be rocked about its pivot so that its inner end is lowered. The lowering of the inner end of the lever 275 permits the vertically extending

rod 278 to be drawn down under action of the spring 280 so that the lever 283 will be dropped down in front of the abutment 104 carried by the reciprocating bars 82. When 5 any one of the accumulating gear wheels has made a complete revolution the reciprocating bar 82 associated therewith will of necessity be in its extreme rearward position. Both the vertically extending lever 278 and 10 the inner end of the lever 275 descend simultaneously, the lever 275 being locked in its downward position by means of the bell crank 320 and the vertical lever 278 being held in its downward position by means of 15 the coil spring 280. When the parts are in the position above described, the reciprocating cam plate 295 is moved forwardly by means of the levers 298, 307 and their associated elements. A forward movement of 20 the cam plate 295 will engage the inclined cam surface 295' thereon with the roller 294 carried by the inner end of the lever 297 thus raising the roller. The lifting of the roller 294 will rock the lever 285 about its 25 pivot 288 thereby forcing the lever 283 pivoted thereto in a rearward direction and bringing the inner end of the lever 283 into engagement with the abutment 104 made on the upper edge of the reciprocating bar 82, 30 and force the said bar backward a distance sufficient to turn the gear wheel 120 to oscillate the type segment a distance sufficient to rotate back one tooth distance, the accumulator gear wheel with which it is associated. 35 Due to the fact that the abutments 200 are carried by the left hand face of each accumulative gear wheel, the set back mechanism heretofore described of the next adjacent accumulative gear wheel to the left 40 is actuated. In other words, a rotation of one of the accumulative gear wheels will actuate the set back mechanism of the accumulative gear wheel of the next higher order. 45 A brief description of the entire machine thus far described will now be given explaining the sequence of operation of the various mechanisms to print and accumulate the data perforated in the cards which 49 are passed through the machine. 50 As a card is fed through the machine various stop pins 14 are elevated corresponding with the various perforations of the card. The elevation of the stop pins 14 will lower 55 the naught stops 16 in the rows in which the stop pins are elevated. The lowering of the stop pins will permit the reciprocating bars 82 associated therewith, to be moved forwardly. The forward movement of the 60 bars 82 will depress the levers 132 which are associated therewith, and these levers will depress all of the levers 132 to the right thereof which have not been depressed by the forward movement of the reciprocating 65 bars associated therewith. All of the levers 132 however, to the left of the lever 132 which has been depressed by the forward movement of the rack bar will still be in their upright position. While the reciprocating bars 82 which have been released 70 are moving forwardly, these last mentioned levers 132 will be reciprocated rearwardly by means of the bell cranks 139 levers 143 and other elements associated therewith, which in their rearward movement will force 75 back the bars 82 with which they are associated, and oscillate the type segments actuated by these rack bars downwardly to a non-print position. The bars 82 move forwardly under the action of the reciprocating bars 89 until the abutments 104 carried on their lower edges come in contact with the various elevated stop pins 14 at which time they come to a rest. When the 80 rack bars 82 have come to a rest, the segments associated therewith have been oscillated upwardly a distance sufficient to set the type thereon in consonance with the number of the stop pin 14. When all of the type 85 segments have been oscillated into proper position the detent 130 is drawn down into engagement with the gear teeth 123 on the type segments and alines and locks them so that they cannot be moved during the print 90 operation. Simultaneous with the operation of the detent, the levers 62 and 163 are actuated, the former causing the drawing down of the set stop pins 14 and elevating all of the naught stops 16, the latter contacting 95 with the reciprocating bars 86 for lowering them so that on their return movement the bell cranks 97 carried thereby will be in a position to rest upon the top of the naught stops 16. The reciprocating printing carriage 13 is then brought into engagement 100 with the type segment and an impression made on the paper carried thereby. The rack bars 82 are now ready for their rearward movement, but previous thereto the reciprocating accumulating carriage has been 105 moved forwardly so that the accumulating gear wheels are brought into engagement with the teeth 123 of the type segments. The locking detent for the type segments is withdrawn and the reciprocating bars 110 moved rearwardly under action of the bar 89. The rearward movement of the rack bars 82 will revolve the accumulating gear wheel through the medium of the type segments and rotate the gear teeth thereon corresponding with the type printed. When the bars 82 have completed their rearward motion, the reciprocating accumulating carriage is also moved rearwardly so as to disengage the accumulative gear wheel from the type segments and to move them into engagement with a transverse bar to lock them against further rotation. All of the elements are now ready for a second forward 115 movement of the reciprocating bars 82, and 120 125 130

the above operation continues. When any of the accumulative gear wheels have made a complete revolution, during which time the bars 82 associated therewith have moved 5 rearwardly into naught stop position, the L-shaped bars 275 are rocked, which through the mechanism heretofore described, will move the rack bar 82 adjacent to the left thereof, back one space so that the accumulative gear wheel associated with this rack bar will also be moved back one space, and in this way form the "carry over."

The above operation continues as the cards pass through the machine and the items 15 thereon are printed by the type sectors and accumulated on the accumulator wheels until either a total card is fed to the machine or until it is desired to take the total of the data accumulated by operating a total key 20 manually. A description of this total taking mechanism will now be given.

All of the actions heretofore described have taken place when the lever 253, which I term the "accumulating lever," is locked by means of the reciprocating cam shaft, to 25 the levers 215. When the total is to be taken the key 140 is lifted either manually or by a push rod A controlled by the perforated cards, as is described in my copending application, Serial No. 80,973, filed Feb. 28, 1916. The reciprocating plunger 236 is released, which will spring into the cam groove 244 and upon engaging therewith will rock the lever 232 about its pivot 233 and reciprocate the cam shaft 255 to the position shown in Fig. 5, which will unlock the accumulating lever 254 and lock the total taking lever 253, whereupon the locking of the levers 207 with the other lever 253 will cause 40 the said lever to reciprocate the accumulating carriage forwardly until the accumulator wheels are brought into contact with the type segments.

At the same time that the cam 255 is reciprocated as above described, means is provided for lowering the pins 14 and the naught stops 16 so that the bars 82 will be in a position to move forward. This means is described in detail in said co-pending application, Serial No. 158,142 and need not be described here.

After the accumulator gear wheels have been moved into mesh with the gear teeth on the type segments and after both the naught stops and the stop pins have been lowered as above described, all the elements will have been set to permit a forward movement of the bars 82. The bars 82 are moved forward under the action of the transverse bar 89 and its associated elements, the said bar 89 being gripped between the abutments 104 and the notches 88 formed in the upper edges of the bars 86. The forward movement of the bars 82 rotate the accumulator gear wheels in the direction

which is anti-clockwise in Fig. 2, until the radial wall of the abutments 200 come into contact with the rear edges of the vertically extending portion of the bar 275. When the accumulating gear wheels have been 70 stopped in the manner heretofore described, they have revolved their associated type segments upwardly a distance sufficient to set into printing position the type corresponding with the gear teeth of the accumulating 75 wheels. Since all of the accumulating wheels will not revolve the same distance, but since it is necessary that the bar 89 should move to the limit of its outward movement, means are provided for releasing 80 the said bar from engagement with the notches 88 formed in the bar 86 so that the bar 89 may slide on the upper edge of the bar 86 as is shown in Fig. 2. These means comprise a lever 350 pivoted to a transverse 85 shaft 351 carried by the cheek plates 189, and is provided on its upper edge with a rounded abutment 353 which is adapted to come in contact with the rounded abutment 203 carried on the collar 199. When the said abutments 203 and 353 come into said contact the lever 350 is forced downwardly, which will force the bars 86 also downwardly through the medium of an outwardly turned lip 354 formed on the outer 90 end of the lever 350. The forcing down of the bars 86 as before described, will release the transverse reciprocating bar 89 and permit it to move downwardly to the limit of its stroke. When all of the type segments 95 have been set up in the manner heretofore described, the detent 130 is brought into contact with the gear teeth of the type segments and locks the said segments in printing position. The reciprocating printing 100 carriage 13 is then moved up into engagement with the type and an impression made 105 on the paper carried thereby. This impression gives the total of the data accumulated by the accumulative gear wheels. 110

After the printing operation is completed the detent 130 is lifted. The bars 82 then move rearwardly during which motion the reciprocating plunger 238 is forced back into its locked position as shown in Fig. 2, 115 and the lever 232 has been rocked about its pivot 233 and thereby reciprocated the cam shaft 225 back to accumulating position. All of the parts are now in the position to accumulate further data.

It is to be understood that all the description thus far has been given relative to the operation of one unit of the machine, that is, one printing and accumulating section composed of 9 type sectors and 9 accumulative gear wheels together with their associated and cooperative elements. It is also to be understood, however, that each unit may contain a greater or less number of associated printing and accumulated elements.

The complete machine, however, comprises a number of units each identical with the unit heretofore described. Means is provided for holding the bars 82, associated with the digits to be kept from printing and accumulating, so that it can not run forward and backward to set type and accumulate and also to hold the bar 82 back far enough to cause the type segment associated therewith to occupy a non-print position. This means comprises a plurality of latch levers 401 (Fig. 2) which are pivotally mounted upon a transverse bar 402 carried between the cheek plates 34 of the machine. When it is desired to render a line of digits inoperative, the reciprocating bar 82 associating therewith is drawn back so that the upper end of the latch lever 401, which is provided with a hook 403 will hook over a horizontally extending pin 404 carried by the vertically extending portion 92 carried by the bar 82.

The printing carriage, designated generally by reference numeral 13 (Fig. 1) is located on the printer tabulator base, opposite the type 126.

The carriage is supported, at opposite ends, on the cam shaft brackets 559 and the lever shaft brackets 601 carried on the base 30 plate of the printer tabulator.

The lever shaft brackets 601 are provided at their upper ends with guide slots 604 in which are received the L-shaped carriage supporting brackets 605 provided at their 35 forward ends with anti-friction rollers 606 adapted to reciprocate in the elongated openings 607.

The printing carriage is carried on these L-shaped brackets and is reciprocated there- 40 with by means of bell-cranks 610 pivoted on a shaft 611 and provided with a roller engaging in a groove on a suitable cam carried on the cam shaft 74. The carriage is recip- 45 rocated so as to bring the paper against type while the type segments are held locked by the detent 130.

The printing carriage is described in detail in said first named co-pending applica- 50 tion.

I claim as my invention:

1. In combination, actuating members; an accumulator associated therewith; and movable members adapted the one to the exclusion of the other to shift the accumulator, 55 and respectively to impart different actions to the accumulator.

2. In an apparatus of the character described, the combination of actuating members; an accumulator adapted to be 60 moved into out of operative relation with the members; a pair of movable members adapted the one to the exclusion of the other to be operatively connected to the accumulator and means for moving the movable 65 members by two different actions.

3. In an apparatus of the character described, the combination of actuating members; an accumulator adapted to be moved into out of operative relation with the members; a pair of movable members 70 adapted the one to the exclusion of the other to be operatively connected to the accumulator and means for moving the movable members by two different actions with movements out of phase with each other. 75

4. In an apparatus of the character described, the combination of actuating members; an accumulator adapted to be moved into and out of operative relation with the members; a pair of movable members adapted the one to the exclusion of the other to be operatively connected to the accumulator; and means for reciprocating the movable members with movements out of phase with each other. 80

5. In an apparatus of the character described, the combination of a plurality of actuating members; an accumulator adapted to be moved into and out of operative relation with the members; an accumulating 85 movable member and a total taking movable member pivotally adapted the one to the exclusion of the other to be operatively connected to said accumulator for moving said accumulator; and accumulating and total taking cams adapted to reciprocate last named members respectively for accumulating or taking totals.

6. In an apparatus of the character described, the combination of actuating 100 members; an accumulator; means operatively connected to the accumulator for moving the latter into or out of operative relation with the actuating members; an accumulating movable member and a total taking 105 member pivotally connected to said means for moving said means and adapted the one to the exclusion of the other, to be operatively connected to said means.

7. In an apparatus of the character 110 described, the combination of actuating members; an accumulator means operatively connected to the accumulator for moving the latter into or out of operative relation with the actuating members; an accumulating 115 movable member and a total taking member pivotally connected to said means for moving said means and adapted the one to the exclusion of the other, to be operatively connected to said means; and means for imparting to said last named members movement for accumulating and taking totals respectively. 120

8. In an apparatus of the character 125 described, the combination of a plurality of actuating members; means for actuating said members selected amounts; and restoring them; an accumulator; a lever-member operatively connected to the accumulator for moving the latter into or out of op- 130

- erative relation with the actuating members; an accumulating lever and a total taking lever pivotally connected to the lever member; and means for locking either of said levers, the one to the exclusion of the other, to said lever member.
9. A lever-member operatively connected to the accumulator for moving the latter into or out of operative relation with the actuating members; an accumulating lever and a total taking lever pivotally connected to the lever members; a longitudinally slideable cam adapted to lock either of said levers, the one to the exclusion of the other, to said lever member; and accumulating and total taking cams adapted to reciprocate said levers respectively for accumulating or taking totals.
10. In an apparatus of the character described, the combination of a plurality of actuating members; means for actuating said members selected amounts and restoring them; an accumulator; a lever-member operatively connected to the accumulator for moving the latter; an accumulating lever and a total taking lever pivotally connected to the lever member; a longitudinally slideable cam adapted to lock either of said levers, the one to the exclusion of the other to said lever member; and accumulating and total taking cams adapted to reciprocate said levers respectively for accumulating or taking totals.
11. A printing tabulator mechanism comprising printing elements, reciprocating members operatively associated therewith, an accumulating mechanism, means for operatively connecting said accumulating mechanism with the printing elements after the printing elements have been actuated by the reciprocating members, and means for operatively connecting the accumulating mechanism and the printing elements before the printing elements have been actuated by the reciprocating members, the means for operatively connecting the accumulating mechanism with the printing elements before and after they have been actuated by the reciprocating members, comprising levers and cams, said levers operated by said cams at different times, one of said levers held inoperative when the other is being actuated by its associated cam.
12. A printing tabulator mechanism comprising printing elements, actuating means therefor, an accumulating mechanism, means for operatively connecting the accumulating mechanism with the printing elements after they have been actuated, means for operatively connecting the accumulating mechanism with the printing elements before they have been actuated; and means for alternately operating each of said connecting means the one to the exclusion of the other.
13. A printing tabulator mechanism comprising printing elements, actuating means therefor, an accumulating mechanism, means for operatively connecting the accumulating mechanism with the printing elements after they have been actuated, means for operatively connecting the accumulating mechanism with the printing elements before they have been actuated, and means for alternately operating each of said connecting means comprising a shiftable member operatively connected with each of said connecting means.
14. A printing tabulator mechanism comprising printing elements, actuating means therefor, an accumulating mechanism, means for operatively connecting the accumulating mechanism with the printing elements after they have been actuated, means for operatively connecting the accumulating mechanism with the printing elements before they have been actuated, means for alternately operating each of said connecting means comprising two pairs of associated levers each pair being connected to the accumulating mechanism, and shiftable means for locking the levers of each pair together.
15. A printing tabulator mechanism comprising printing element actuating means therefor, an accumulating mechanism, means for operatively connecting the accumulating mechanism with the printing elements after they have been actuated, means for operatively connecting the accumulating mechanism with the printing elements before they have been actuated, and means for alternately operating each of said connecting means comprising two pairs of associated levers, each pair being connected to each other and to the accumulating mechanism, said shiftable means comprising a reciprocatable cone shaft.
16. A printing tabulator mechanism comprising printing elements, actuating means therefor, an accumulating mechanism, means for operatively connecting the accumulating mechanism with the printing elements after they have been actuated, means for operatively connecting the accumulating mechanism with the printing elements before they have been actuated, means for alternately operating each of said connecting means comprising two pairs of associated levers, each pair being connected to each other and to the accumulating mechanism, said shiftable means comprising a reciprocatable cone shaft, and means for reciprocating said cone shaft comprising a cam and a lever operatively connected thereto and to the said cone shaft.
17. A printing tabulator mechanism comprising printing elements, an accumulating mechanism, means for moving the said accumulating mechanism into operative relation with the printing elements, said means

comprising lever members pivoted together, and a member engaging the lever members for making the pivot a rigid connection.

18. A printing tabulator mechanism comprising printing elements, an accumulating mechanism, means for moving the said accumulating mechanism into operative relation with the printing elements, said means comprising levers pivoted together, and a member engaging the levers for making the pivot a rigid connection, said member comprising a shaft passing thru registering openings in the levers.

19. A printing tabulator mechanism comprising printing elements, an accumulating mechanism, means for moving the said accumulating mechanism into operative relation with the printing elements, said means comprising levers having one end pivoted to the accumulating mechanism, arms pivoted to the other ends of the said levers, and a slideable shaft extending thru the arms and the levers providing means whereby their pivot connection is made rigid.

20. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, and a slideable cone shaft fitting in said openings providing means for locking the said arms rigidly to the said levers.

21. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, and a slideable cone shaft fitting in said openings providing means for locking the said arms rigidly to the said levers, the said cone shaft having cones arranged whereby the said driving arms are alternately locked to their associated lever.

22. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, a slideable cone shaft fitting in said openings providing means for locking the said arms rigidly to the said levers, the said cone shaft having cones arranged whereby the said driving arms are alternately locked to their associated lever, and cams operatively associated with said driving arms for operating them.

23. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, a slideable cone shaft fitting in said openings providing means for locking the said arms rigidly to the said levers, and means for holding the cone shaft in a position to hold one of the arms locked to its associated lever.

24. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers, and having an opening therein, a slideable cone shaft fitting in said openings providing means for locking the said arms rigidly to the said levers, means for holding the cone shaft in a position to hold one of the arms locked to its associated lever, and means for releasing said holding means.

25. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers, and having an opening therein, a slideable cone shaft fitting in said openings providing means for locking the said arms rigidly to the said levers, means for holding the cone shaft in a position to hold one of the arms locked to its associated lever, means for releasing said holding means and means for sliding the cone shaft for releasing the locked arm and locking the other arm to its associated lever.

26. A printing tabulator mechanism comprising printing elements, an accumulating mechanism, means for moving the said accumulating mechanism into operative relation with the printing elements, said means comprising levers composed of pivoted links, and resilient means carried by said links for holding the links against movement on their pivots.

27. A printing tabulator mechanism comprising printing elements, an accumulating mechanism, means for moving the said accumulating mechanism into operative relation with the printing elements, said means comprising levers composed of pivoted links, lugs for limiting the movement of the links on their pivots, and resilient means carried by said links for holding the levers against the said lugs.

28. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, a slidable cone shaft fitting in said openings providing means for locking the said arms rigidly to the said levers, means for holding the cone shaft in a position to hold one of the arms locked to its associated lever, means for releasing said holding means for sliding the cone shaft for releasing the locked arm and locking the other arm to its associated lever, said means comprising a slidable lever attached to the cone shaft, a cam, and means for operatively connecting said lever with said cam.

29. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and each having an opening therein, a slidable cone shaft fitting in said openings providing means for locking the said arms rigidly to the said levers, means for holding the cone shaft in a position to hold one of the arms locked to its associated lever, means for releasing said holding means for sliding the cone shaft for releasing the locked arm and locking the other arm to its associated lever, said means comprising a slidable lever attached to the cone shaft, two cams, and means for normally holding the said lever in operative connection with one of said cams.

30. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and each having an opening therein, a slidable cone shaft fitting in said openings providing means for locking the said arms rigidly to the said levers, means for holding the cone shaft in a position to hold one of the arms locked to its associated lever, means for releasing said holding means for sliding the cone shaft for releasing the locked arm and locking the other arm to its associated lever, said means comprising a slidable lever attached to the cone shaft, two cams, means for normally holding the said lever in operative connection with one of said cams, and means for releasing the holding means and locking the lever with the other cam.

31. A printing tabulator mechanism com-

prising printing elements, an accumulating mechanism, means for moving the said accumulating mechanism into operative relation with the printing elements, said means comprising two levers connected to the accumulating mechanism, driving arms pivoted to the said levers and each having an opening therein, a slidable cone shaft fitting in said openings providing means for locking the said arms rigidly to the said levers, means for holding the cone shaft in a position to hold one of the arms locked to its associated lever, means for releasing said holding means for sliding the cone shaft for releasing the locked arm and locking the other arm to its associated lever, said means comprising a slidable lever attached to the cone shaft, a cam, a reciprocating plunger carried by the slidable lever, and means for operatively connecting the said plunger with the cam.

32. A printing tabulator mechanism comprising printing elements, an accumulating mechanism, means for moving the said accumulating mechanism into operative relation with the printing elements, said means comprising two levers connected to the accumulating mechanism, driving arms pivoted to the said levers and having an opening therein, a slidable cone shaft fitting in said openings providing means for locking the said arms rigidly to the said levers, means for holding the cone shaft in a position to hold one of the arms locked to its associated lever, means for releasing said holding means for sliding the cone shaft for releasing the locked arm and locking the other arm to its associated lever, said means comprising a slidable lever attached to the cone shaft, two cams, a reciprocating plunger carried by the slidable shaft, means for holding the said plunger out of contact with the cam, and means for releasing the plunger and operatively connecting it with the cam for the purpose described.

33. In combination, actuating members; an accumulator; means for moving the accumulator to operative relation with the actuating members comprising a device having a motive portion and an active portion movable relative to the motive portion and operatively connected to said accumulator; means for moving the motive portion; and a yieldable means interposed between said portions.

34. In combination, actuating members; an accumulator; a member having a motive portion and an active portion, the latter operatively connected to said accumulator; means for moving the motive portion; and a yieldable means interposed between said portions.

35. In combination, actuating members; an accumulator; a member having a motive portion and an active portion movable rel-

ative to the motive portion operatively connected to said accumulator; means for moving the motive portion; a yieldable means connecting said portions, and means for limiting movement of the active portion relative to the motive portion under the action of the yieldable means.

36. In combination, actuating members; an accumulator; a member having a motive portion, and an active portion operatively connected to the accumulator and movable relative to the motive portion to permit the accumulator to leave the actuating members; a yieldable means connecting said portions, and means for limiting movement of the active portion relative to the motive portion under the action of the yieldable means.

37. In combination, a plurality of actuating members; a reciprocatory accumulator; a lever having an active arm comprising an inner fulcrumed link and an outer link operatively connected to said accumulator; means for reciprocating the fulcrumed link; a yieldable spring means connecting said links; and means for limiting movement of the outer link, relative to the fulcrumed link, under the action of the spring means.

38. In combination, a plurality of actuating members; an accumulator; a reciprocating carriage for said accumulator intermediately fulcrumed levers having the free ends of their active arms operatively connected to said carriage for reciprocating the latter; each active arm comprising a pair of pivotally connected links adapted for pivotal movement in one direction and positively held from pivotal movement in the other direction; resilient means for holding said links against relative movement in the first named direction; and means for reciprocating the motive arm of the levers.

39. In an apparatus of the character described, adapted for accumulating or taking totals; a movable total shift member for causing total taking; a cam provided with a shifting cam groove; a plunger slidably mounted on said member and adapted to be engaged in said groove; and means for causing the plunger to engage the groove.

40. In an apparatus of the character described, the combination of an accumulator; means for actuating the accumulator and comprising a shiftable means for adapting the actuating means for accumulating or taking totals; a movable total shift member engaging said shiftable means; a cam providing a shifting groove; a plunger slidably mounted on said member and adapted to be yieldably pressed into said groove; means in the groove for retracting the plunger from the groove; means for holding the plunger in retracted position; and means for releasing the retaining means.

41. In an apparatus of the character described, the combination of an accumulator;

means for reciprocating the accumulator for taking totals or accumulating and comprising a shiftable means shiftable one way or another for causing accumulating or total taking; a total shift lever; a cam provided with a spiral peripheral cam groove adapted to receive said plunger head and terminating in a cam end-abutment; a spring tending to hold said plunger into said groove thereby to shift the lever; a pawl intermediately pivoted on said lever and adapted to engage said head for holding the plunger retracted; and means for engaging and operating said pawl.

42. In an apparatus of the character described; a total-taking mechanism comprising a shiftable means for adapting said mechanism for the total-taking operation; a movable shift member engaging said shiftable means; a cam providing a shifting groove; a plunger slidably mounted on said member and adapted to be yieldably pressed into said groove; means for retracting the plunger from the groove; means for holding the plunger in retracted position; and means for releasing the retaining means.

43. In an apparatus of the character described, a total taking mechanism comprising a shift lever comprising spaced parts; a plunger slidably mounted in said parts and provided with a cam engaging plunger head on one end and a retaining collar at the other end; a cam provided with a spiral peripheral cam groove adapted to receive said plunger head and terminating in a cam end-abutment; a spring tending to hold said plunger into said groove thereby to shift the lever; a pawl intermediately pivoted on said lever and adapted to engage said head for holding the plunger retracted; and means for engaging and operating said pawl.

44. In an apparatus of the character described for accumulating or taking totals; an accumulator; means for operating the accumulator to accumulate or to cause totals to be taken; cams for determining which operation shall take place; and means operated by a cam for selecting the cam to accumulate or take totals.

45. In an apparatus of the character described for accumulating or taking totals; an accumulator; means for operating the accumulator to accumulate or to cause a total to be taken; means for shifting one to the other; cam operated means for controlling the shift; and means for bringing into action at will the said cam operated means.

WILLIAM W. LASKER.
